William Heickman. Dolman

UNITED STATES PATENT OFFICE.

WILLIAM H. DOLMAN, OF ST. HELEN, OREGON.

FIRE-PROOF BUILDING.

SPECIFICATION forming part of Letters Patent No. 286,401, dated October 9, 1883.

Application filed January 22, 1883. (No model.)

To all whom it may concern:

Be it known that I, WILLIAM HICKMAN DOLMAN, a citizen of the United States, residing at St. Helen, Columbia county, and State 5 of Oregon, have invented a new and useful Fire-Damper, by which I prevent the destruction by fire of houses, buildings, and structures, and of rafters, joists, timbers, posts, caps, and sills used in their construction, and according 10 to my knowledge and belief the same has not been in public use for more than two years prior to this application in this country; and I hereby declare that the following is a full, clear, and exact description of the invention, 15 which will enable others skilled in the art to which it appertains to make and use the same.

Heretofore, when fire could not be subdued by the means at hand, the total destruction of a building and its contents was accomplished 20 in a few minutes. When the fire had once eaten a hole through the floor and roof, the whole structure was converted into a furnace.

The object of my invention is, by means of sheet-iron and ashes or any fine pulverized dry 25 uninflammable earth, to dampen and smother the fire; to prevent fire from ascending above or descending below the room or story in which it originated; to prevent the fire from a burning roof from descending to the attic or to any 30 lower room or story, and to prevent fire that has started in a cellar from ascending to any room or story above. I attain these objects and results by the mechanism illustrated in the 35 accompanying drawing, which represents a section of a floor, the ends of the joists, and the ceiling of a building.

Similar letters refer to similar parts.

The joists E E having been set in place in the wall of the building, I securely nail or 40 fasten to the bottom or under edge sheet-iron e e. This sheet-iron may vary from No. 24 to 30, American gage. One sheet should lap on another from three-fourths of an inch to one inch. All the joists E E must be thus 45 protected on the bottom or under edge, forming a ceiling of sheet-iron. I then deposit on this sheet-iron e e, and between the joists E E, two to four inches in depth of fine sifted dry ashes or earth G G, banking the ashes or earth 50 well up against the sides of the joists E E. I then nail strips of board a a to the side of the joists one and a half inch to three inches below

the upper edge or top of the joists. I then securely nail sheet-iron b b onto the strips a a. I then commence laying the floor A, and as the 55 laying progresses I entirely fill the space F F between the floor A and the sheet-iron b b with ashes or earth, taking care that there is no hollow space under the floor A, in which the air can circulate, and that no chips of wood or 60 any other combustible material is mixed with the ashes or earth. If the ceiling B is to be plastered, I nail strips d d on the sheet-iron e e firmly to the joists E E, to which lath can be nailed to receive the plastering. This 65 leaves a small space, x x, the object of which is to prevent the sheet-iron e e from resting on the lath and plastering, and leaving a space for the mortar to key. A dead-air space, K K, 70 between the ashes or earth G G and the sheet-iron b b, is left to prevent dampness. In the event of fire breaking out in the room or story of which A represents the floor, usually not all of the floor A will be consumed, as the ashes or earth F F will smother and dampen 75 the under side of the flooring-boards to the extent of preventing rapid and total burning, and in no case is it possible for a fire on floor A to reach and burn more than a small part of the upper edge or top of joists E E, while 80 the ashes or earth F F is held in place, as the ashes or earth F F will smother and dampen the fire there and put it out. Should a fire break out in the room or story of which B is 85 the ceiling, it is highly probable that the lath and plastering and the strips d d would be destroyed; but it is not possible that any ordinary fire starting on that story could heat the ashes or earth G G sufficiently hot to fire the 90 joists E E. The action of the ashes or earth G G is to dampen the heat that rises to sheet-iron e e, and to smother the joists E E and prevent their taking fire. At the place where the joists E E enter the wall the entire space K K should be filled with the ashes or earth G G, 95 thus preventing the joists E E taking fire from or through the walls that might be heated from a neighboring conflagration.

The opening Y is shown as closed by the trap-door D, resting on a shoulder in sheet-iron Z, filled with ashes or earth H. To prevent the wood-work from burning at any opening in the floor or roof, and to stop the draft or fire being carried up or down, I nail sheet-

iron Z to the side of the wood-work, as shown at joist E, leaving a space, H, of two or three inches, between the sheet-iron Z and the joist E, which I fill with ashes or earth. It is very important that all the wood-work at all the openings should be thus protected. The trap-door D is made of sheet-iron, is of a thickness of two to four inches, and the hollow space J filled with ashes or earth. This trap-door D should be made to open and close freely, and when up should be so held by a cotton or other cord made from some inflammable material, and should never be fastened up by any metal fastening.

I am aware that prior to my invention iron joists, brick, tiles, and mortar have been used to construct fire-proof floors.

I am also aware that sheet-metal arched plates have been inserted between the joists of a floor in the same plane, near the upper faces of the joists, a part of said plates projecting up above the upper faces of the joists to form, on the upper face of each joist, a cham-

ber having three sides, and that the space between the top of the arched plates and the 25 flooring, and also the chambers formed on the top of each joist, have been filled in with plaster or other fire-proof material, and the flooring nailed to the joists through the fire-proof material in the chambers described, and I 30 therefore lay no claim to such construction, my invention being confined to the peculiar construction pointed out in the claim.

What I do claim as my invention, and desire to secure by Letters Patent, is—

The combination, with the joists E, each provided with the strips *a a d*, of the continuous sheet-iron ceiling e, plates b, continuous between two joists, fire-proof material F G, and laths and plastering B, substantially as 40 shown and described.

WILLIAM HICKMAN DOLMAN.
